H. F. ACKERMAN AND J. F. HABBEK.
RADIATOR.

APPLICATION FILED MAR. 30, 1921.

1,405,381.

Patented Feb. 7, 1922.

UNITED STATES PATENT OFFICE.

HENRY F. ACKERMAN AND JOHN F. HABBEN, OF PALMER, IOWA.

RADIATOR.

1,405,381.

Specification of Letters Patent. Patented Feb. 7, 1922.

Application filed March 30, 1921. Serial No. 456,957.

To all whom it may concern:

Be it known that we, HENRY F. ACKERMAN and JOHN F. HABBEN, citizens of the United States, residing at Palmer, in the 5 county of Pocahontas and State of Iowa, have invented certain new and useful Improvements in Radiators, of which the following is a specification, reference being had to the accompanying drawings.

10 This invention relates to certain improvements in radiators and has relation more particularly to a device of this general character comprised in the cooling system for an internal combustion engine or the like, and 15 it is an object of the invention to provide a novel and improved device of this general character embodying water tubes of such cross sectional configuration to substantially eliminate the possibility of freezing.

20 Another object of the invention is to provide a novel and improved device of this general character embodying a plurality of series of vertically disposed water tubes, the tubes of one series being staggered with respect to the tubes in the adjacent series and 25 wherein the forward and rear portions of each of the tubes are restricted or crimped, thus providing said tube with an increased cooling surface and also providing means 30 whereby said tube can expand in the event the water therein should freeze.

An additional object of the invention is to 35 provide a radiator including a tank and wherein said tank has arranged therein novel and improved means to facilitate the cooling of the water.

The invention consists in the details of construction and in the combination and arrangement of the several parts of our 40 improved radiator whereby certain important advantages are attained and the device rendered simpler, less expensive and otherwise more convenient and advantageous for use, as will be hereinafter more fully set forth.

45 The novel features of our invention will hereinafter be definitely claimed.

In order that our invention may be the better understood, we will now proceed to describe the same with reference to the accompanying drawings, wherein:

Figure 1 is a vertical sectional view taken through a radiator constructed in accordance with an embodiment of our invention;

Figure 2 is a fragmentary sectional view taken substantially on the line 2—2 of 55 Figure 1;

Figure 3 is a vertical sectional view taken substantially on the line 3—3 of Figure 1;

Figure 4 is a fragmentary horizontal sectional view taken substantially on the line 60 4—4 of Figure 1; and

Figure 5 is an enlarged fragmentary view illustrating in detail a seam comprised in the structure of each of the water tubes or flues.

As disclosed in the accompanying drawings, R denotes a radiator in its entirety constructed in accordance with an embodiment of our invention and which includes the upper tank 1, the lower tank 2 and the sides 3. Connecting the tanks 1 and 2 are the vertically disposed water tubes 4 preferably arranged in three series with the tubes of each series in transverse alignment and with the tubes of one series staggered with respect to the tubes of the adjacent series. For this 75 reason, in practice, the second or intermediate series of tubes is one less in number than the remaining two series.

Each of the tubes 4 has its forward and rear portions crimped or reduced, as at a. 80 Each of the tubes is formed from a single sheet of material with the connecting seam 5 double gripped and soldered. The tubes or pipes 4 are so arranged, in practice, that no part of any one tube or pipe is spaced 85 more than one-quarter of an inch from any corresponding point on adjoining or adjacent tubes or pipes.

The tubes or pipes 4 are so arranged that the air as it passes between the first or outer 90 series of tubes or pipes splits on the front edges of the intermediate series of tubes or pipes so that substantially the same amount of air strikes each pipe on two sides, thus giving it a greater cooling surface than if 95 the air hit each pipe on only one side. This is also true of the air as it passes the second series of tubes or pipes and strikes the tubes or pipes in the third or inner series.

The cross sectional configuration of each 100 of the tubes or pipes 4 is such that in the event the water therein should freeze, the crimped portions of said pipes can expand substantially one-fifth of an inch and when said tube is thawed out, the pipe or tube will 105 return to its former or normal cross sectional

form due to the cross sectional shape of the sides *a* of the reduced or crimped portion of the tube.

The rear portion of the upper tank 2 at 5 its bottom has in communication therewith in a conventional manner the cylinder outlet hose. Disposed vertically within the rear portion of the tank is a partition 6, herein disclosed as substantially semicircular in 10 cross section and bridging the space between the top and bottom walls of the upper tank 1. The cylinder outlet hose communicates with the upper tank 1 within the chamber afforded by this partition. This partition 15 is provided with the openings 7 preferably one-quarter of an inch in diameter and spaced apart about one-quarter of an inch.

The upper tank 1 in advance of the partition 6 is provided entirely thereacross with 20 a straight partition 8 provided adjacent its lower corners with the openings 9 each preferably about three-quarters of an inch square. The central portion of this partition 8 about 25 two inches from its top is provided with an opening 10 preferably substantially three-quarters of an inch in diameter. Interposed between the partition 8 and the front wall 11 of the upper tank 1 is a horizontally disposed partition 12 preferably located about 30 three inches from the top of the upper tank with the openings 14 positioned directly 35 above the tubes 4, each of said openings being substantially three-eighths of an inch in diameter and spaced apart about one-quarter of an inch.

The various partitions in the upper tank 1 retard the flow of the water so that such water must be forced through the openings in the partitions before the same can enter 40 the tubes or pipes 4. This operation causes to a certain extent a spray with the resultant consequences of a tendency to further cool the water.

From the foregoing description it is 45 thought to be obvious that a radiator constructed in accordance with our invention is particularly well adapted for use by reason of the convenience and facility with which it may be assembled and operated, and it will 50 also be obvious that our invention is susceptible of some change and modification without departing from the principles and spirit thereof and for this reason we do not wish to be understood as limiting ourselves

to the precise arrangement and formation 55 of the several parts herein shown in carrying out our invention in practice except as hereinafter claimed.

We claim:

1. A radiator for a cooling system for an 60 internal combustion engine embodying an upper tank, a lower tank and water tubes connecting said tanks, said tubes having their forward and rear portions restricted, said tubes being arranged in a plurality of 65 series, the tubes of each series being transversely alined, the tubes of one series being staggered with respect to the tubes of the adjacent series, each tube at all points being substantially equidistantly spaced from the 70 adjacent tubes.

2. A radiator for a cooling system for internal combustion engines comprising an upper tank, a lower tank, tubes connecting said tanks, said upper tank being provided 75 with an inlet, a vertically disposed perforate partition connecting the upper and lower walls of the upper tank and providing a chamber with which the inlet communicates, and a vertically disposed partition extending 80 across the upper tank in advance of the first named partition and provided with openings in its upper and lower marginal portions.

3. A radiator for a cooling system for 85 internal combustion engines comprising an upper tank, a lower tank, tubes connecting said tanks, said upper tank being provided with an inlet, a vertically disposed perforate partition connecting the upper and lower 90 walls of the upper tank and providing a chamber with which the inlet communicates, a vertically disposed partition extending across the upper tank in advance of the first named partition and provided with openings in its upper and lower marginal portions, and a horizontally disposed partition 95 extending across the upper tank and interposed between the second named partition and the front wall of the upper tank, said last named partition being provided with 100 openings positioned substantially directly above the vertical tubes.

In testimony whereof we hereunto affix our signatures.

HENRY F. ACKERMAN.
JOHN F. HABBEN.
